UNITED STATES PATENT OFFICE.

OTTO VON BRONK, OF BERLIN, GERMANY, ASSIGNOR TO GESELLSCHAFT FÜR DRAHT-LOSE TELEGRAPHIE M. B. H., OF BERLIN, GERMANY, A CORPORATION OF GERMANY.

APPARATUS FOR CONVERTING SOUND WAVES INTO ELECTRIC WAVES.

Application filed April 3, 1924, Serial No. 703,831, and in Germany May 25, 1923.

My invention relates to means for converting sound waves into electric waves.

It has for its object the provision of such an arrangement, which, by the use of what 5 may be called a thermal microphone, will provide accurate and large current variations from a given sound wave.

Other objects will be apparent from the following description, when considered with 10 the accompanying drawings, in which:

Fig. 1 shows a circuit containing a thermal microphone according to the invention.

Fig. 2 shows a modification in which the thermal microphone is coupled directly to a 15 thermionic valve.

Fig. 3 shows a further modification in which a Wheatstone bridge is employed.

Fig. 4 shows an arrangement in which the differential effects of the bridge shown in 20 Fig. 3 is amplified by means of a thermionic valve before being utilized.

The invention relates to an arrangement 25 for converting sound waves into electric oscillations which differs from other arrangements in that the sound wave is not distorted by natural oscillations of the system. The invention is based upon the principle that the temperature and therefore also the conductance of a glowing body is altered by sound waves being impressed on it. These 30 variations of resistance alter according to the shape of the sound waves, the voltage of a circuit which variations may be coupled to the grid of a thermionic valve.

Referring to Fig. 1, 14 is a thermal microphone comprising a frame 1, consisting, for instance, of soap-stone on which the body 2, which is to be rendered incandescent is fastened in zigzag shape. This body 2 may consist, for instance, of a thin platinum wire or an alloy of high resistance coefficient. The ends 3 and 4 of the incandescent wire 40 are connected in circuit with the regulating resistance 5, the current source 6, furnishing the heating current and a winding 7 of transformer 8. The other winding 9 of transformer 8 is connected to the grid 10 and cathode 11 of a three element thermionic tube 12 which also contains plate 13.

It can easily be seen that the sound waves falling upon incandescent wires 2 vary the resistance of these wires in accordance with their form in the well-understood manner. The variations of current in winding 7 will

induce similar variations in winding 9 of 55 transformer 8 which variations are impressed on the filament 11 and grid 10 of tube 12. The tube 12 will amplify these variations and the amplified variations can be led off from the plate 13 and filament 11. 60

Referring to Fig. 2 the thermal microphone 24 is connected in circuit with regulating resistance 25 and battery 26 which supplies the heating current for microphone 24. Microphones 24 may be similar to microphone 65 14, described in connection with Fig. 1. Across terminals 33 and 34 of microphone 24 is connected the grid 20 and filament 21 respectively of thermionic tube 22. Battery 35 is an auxiliary grid battery to obtain 70 conditions suitable for the best working of tube 22. Across plate 23 and filament 21 of tube 22 is a circuit including B-battery 36 and receiver 37.

It will easily be seen that the voltage 75 across the terminals 33 and 34 will vary according to the sound waves impressed on the incandescent wires 32. These variations are impressed on the grid 20 of tube 22 and will produce similar but much larger 80 variations in the receiver 37 in accordance with the amplifying action of the tube 22. The incandescent body 32 may consist of a metal or of a conductor of negative temperature coefficient as, for instance, carbon or the 85 rare materials of the Nernst glowers.

In order to increase the effect, two kinds 90 of materials, one with negative and the other with positive temperature coefficients can be used together for one grid, the single rods of which consist alternately of these materials. When such a grid is connected in a Wheatstone bridge connection to a receiver, the differential effect of the alteration of resistance acts on the receiver. 95

Such a connection is schematically shown in Figure 3. Two arms of the bridge contain two bodies 43 and 44 of positive and negative temperature coefficients respectively heated by the common battery 46 across the regulating resistance 45, which makes up the 100 other two arms of the bridge. The diagonal branch of the bridge contains the telephone 47. It is obvious that if the resistances 43 and 44 are altered simultaneously in opposite sense, the balance of the bridge is disturbed and a differential effect occurs in the telephone. 105

In Fig. 4 the differential effect obtained by utilizing elements 43 and 44 in the bridge having respectively positive and negative temperature coefficients is amplified by 5 thermionic tube 52 before utilization. The amplified potential differences may be used for actuating a telephone 57 or if desired may be fed to the modulator of a radio broadcast transmitter.

10 My invention is not limited to the specific embodiments described above but is entitled to all modifications that fairly fall within the scope of the following claims.

I claim:

15 1. In an arrangement for converting sound waves into electric oscillations, a plurality of heated elements whose electric conductivity is varied by the action of sound waves, said heated elements consisting of two dissimilar substances of separate positive and 20 negative temperature coefficients and means to incorporate said substances into a bridge circuit, whereby a differential effect is obtained.

25 2. In a system for converting sound waves

into electrical oscillations, a bridge circuit having in two of its arms heated elements having positive and negative temperature coefficients respectively, said elements being arranged so that sound waves impinging 30 simultaneously on both of them cause unbalancing of the bridge and also being arranged so that the differences in potential across the bridge due to the unbalancings caused by the sound waves may be amplified 35 by a vacuum tube.

3. In an arrangement for converting sound waves into electrical undulations, a plurality of heatable elements separately 40 having positive and negative temperature coefficients, the conductivity of said elements being variable under the action of sound waves, said elements being connected together so as to obtain a differential effect when affected by sound waves, and being so 45 connected together as to allow the coupling of means responsive to current changes, thereto.

OTTO VON BRONK.
